UNITED STATES PATENT OFFICE.

CARL ERNESTUS AND WILHELM LUSEBRINK, OF ELBERFELD DONBERG, GERMANY.

DEVICE FOR THE MANUFACTURE OF TAPE, WEBBING, GIMP, BRAID, AND SIMILAR MATERIALS.

Application filed March 12, 1926, Serial No. 94,152, and in Germany February 25, 1925.

The object of the present invention is a device for the manufacture of tape, webbing, gimp, braid and similar materials.

The invention permits of a single machine being used for the manufacture of tape, webbing, gimp and braid, whereas, for the production of these materials, separate machines have formerly been necessary. Moreover, with the present machine it is possible, through a suitable rotary movement of the plate spool system in relation to the striker spool system, for the wrapped or webbed threads to be twined without any special mechanism or working process being necessary for this purpose. The device in accordance with this invention consists in two or more spool systems which have a circular or orbital track, in which the spools at times overlap one another, having a common dissecting arc and between which spool systems, in the centre of their joint circular track surface, a binding thread is carried upwards. The spools of the one system rest on arched revoluble strikers, while the spools of the adjacent system are fixed to a revoluble plate. To provide clearance for the spools on the joint circular track surface, the spools, moreover, precede each other. Thus, the track for the striker and that for the spool plate are displaced vertically in relation to each other, and the former is suitably cut away at the place of overlapping to correspond with the size of the arch of the plate. In order that the strikers shall not be able to leave the track, they are made longer than the cut-away portion of the track at the place of overlapping. The spool for the binding thread can be fixed in a suitable manner to the stationary spindle of the plate system, and the device for carrying up this thread preferably consists of a small plate fixed to this spindle and provided with loops, which plate extends under the striker as far as the centre of the joint circular track surface. The drive of the strikers and of the plate is taken from a joint shaft, in such a manner that for the striker both an interior and exterior drive can be used and both systems can be driven in the same direction as well as in opposed directions. In the latter case, a kind of twining of the wrapped threads or cable strands takes place, although the two systems as well as the binding thread never change their positions in relation to each

other so that they therefore have a constant relative position.

In the drawing the invention is represented by way of example.

Fig. 1 is a plan, and 60
Fig. 2 a section along the line 2—2 of Fig. 1.

Similar letters of reference denote corresponding parts throughout the several views.

On the base-plate *a* are fitted the spindles *b* and *c*. These spindles are hollow, and through them the thread to be wrapped is carried to and fro. On the spindle *b* rests the plate *d* which carries the spool spindles *e* and *e*¹ which are represented in plan in 65 broken lines. The spindle *c* carries the sprocket *f* which through transmission gear wheels actuates the arched strikers *g* and *g*¹. These arched strikers which are provided in the known manner with teeth *h* and *h*¹ 70 carry the spools *i* and *i*¹ of the striker system which are shown in the drawing in broken lines. The spool spindles *e* and *e*¹ of the plate system run counter to the spools *i* and *i*¹ of the striker system, when the striker system and the plate system rotate in the same direction. On the other hand, when the striker system and the plate system travel in opposed directions, as is shown in the drawing by the arrow, the one system follows the other in such a manner that the spools always escape each other at the position where the striker and plate systems overlap in their rotary movement. 75

The planes of the strikers *g* and of the plate *d* are relatively displaced in a vertical direction so that the strikers *g* and *g*¹ can be moved back over the plate *d*. Further, the gang face *t* for the strikers *g* is provided with a cut-out portion *t*¹ in the direction of 80 the diameter of the plate, so that the spool spindles *e* and *e*¹ can cross unhindered with the spool *i* and *i*¹. Now to provide for the strikers *g* and *g*¹ being mechanically carried back over this cut-out portion, the said 85 strikers are made longer than the arched portion of the striker gang face *t* which corresponds to this cut-out portion. On the spindle *b* is firmly secured the spool for the binding thread *m* which lies upon the disc *l*. This thread *m* is led through loops *n* and *o* 90 which are disposed in a sheet or strip *p* fixed to the spindle *b* underneath the striker *g* through the centre of the joint circular track surface of the spools *e* and *i* and upwards, 95 100 105 110

so that this binding thread *m* is at one time intertwined by the thread of the striker spool and at another time by the plate spool or by the corresponding windings. A binding of this nature i. e. with the use of a binding thread, is, however, eliminated when making braids and cords. It is, of course, quite permissible for several such devices to be used side by side either in a straight line or in circle form.

The wrapping of a cable wire with division of the desired colours is effected in the following manner. A cable core is carried through each of the spindles *c* and *b* and with the striker spools *i* and *i*¹ for example a green colour can be used and on the plate spools *e* and *e*¹ for example a black colour can be used. Through the rotation of the striker spools the cable is first wrapped with green in the spindle *c* and through the rotation of the plate spools the cable in the spindle *b* is wrapped with black, whereby the binding thread is intertwined with both colours. By virtue of the fact that the plate and the striker now rotate in the same direction, these wrapped cables are simultaneously intertwined with each other in the manner previously indicated.

It is, of course, also possible to manufacture a cable in which the separate cable wires are not intertwined. When this form of cable is required, the separate cable wires with the assistance of the binding thread are bound firmly together in a straight line. In this case the striker and plate work in opposed directions. This method of procedure has the advantage of a great economy in labour in comparison with the known types of machines in which, in order to divide the colours, it is necessary first to wrap each cable core separately and then to intertwine these wrapped cables together.

For the manufacture of striped or tucked materials several apparatus such as are indicated in the drawing can be built close together in a circle, in which case, for the manufacture of a tape furnished with white bands, the left and right spools on the complete series are fitted with white thread, while the spools lying between them are fitted with black thread, whereby the cable core carried upwards in the spindles *a* and *b* is dispensed with. The binding of these separate windings produced by the spool gangs occurs in the same way as previously described, viz the spools of the striker grip round the binding thread on the one side, while the spools of the plate grip round the binding thread on the other side.

An essential advantage of the invention consists in that it is possible to produce a larger output in comparison with the class of machines in use for the separate operations.

Having now described our invention, what

we claim and desire to secure by Letters Patent is:—

1. A device for the manufacture of tape, webbing, gimp, braid and similar materials comprising in combination two independent spool systems distanced apart and adapted for revolution in the same or in opposite directions, means for driving the systems, spool spindles relatively spaced apart on the respective systems which are so arranged that the one system overlaps the other and a binding thread fed to the device so that it is guided upwardly in the centre of the joint circular track provided by the two systems where they intersect. 70 75

2. A device for the manufacture of tape, webbing, gimp, braid and similar materials comprising in combination a plate spool system and a striker spool system, distanced apart and adapted for revolution in the same or in opposite directions so that the one overlaps the other, means for driving the systems, spool spindles carried by the plate system and spool spindles fixed to arched members constituting the striker system, the spindles on each system being relatively spaced apart in such a manner that the spools of one system precede the spools of the other system to provide a reciprocal clearance between the two circular tracks 85 90 and a suitable binding thread fed to the device so that it is guided upwardly in the centre of the joint circular track provided by the two systems where they intersect. 95

3. A device for the manufacture of tape, 100 webbing, gimp, braid and similar materials comprising in combination a plate spool system and a striker spool system distanced apart and adapted for revolution in the same or in opposite directions so that the one overlaps the other, means for driving the systems 105 from a joint shaft enabling an interior or an exterior drive to be employed for the strikers, spool spindles carried by the plate system and spool spindles fixed to arched 110 members constituting the striker system, the spindles on each system being relatively spaced apart in such a manner that the spools of one system precede the spools of the other system to provide a reciprocal clearance between the two circular tracks and a suitable 115 binding thread fed to the device so that it is guided upwardly in the centre of the joint circular track provided by the two systems where they intersect. 120

4. A device for the manufacture of tape, webbing, gimp, braid and similar materials comprising in combination a plate spool system and a striker spool system distanced apart and the one vertically displaced in relation to the other both adapted for revolution in the same or in opposite directions, the track of the striker system being suitably cut-away to enable the unhindered crossing of the plate spools, means for driv- 125 130

- ing the systems from a joint shaft enabling an interior or an exterior drive to be employed for the strikers, spool spindles carried by the plate system and spool spindles fixed to arched members constituting the striker system, the spindles on each system being relatively spaced apart in such a manner that the spools of one system precede the spools of the other system to provide a reciprocal clearance between the two circular tracks and a suitable binding thread fed to the device so that it is guided upwardly in the centre of the joint circular track provided by the two systems where they intersect. 40
- 10 6. A device for the manufacture of tape, webbing, gimp, braid and similar materials comprising in combination a plate spool system and a striker spool system distanced apart and adapted for revolution in the same or in opposite directions so that the one overlaps the other, hollow spindles centrally arranged upon the two systems, means for driving the systems, spool spindles carried by the plate system and spool spindles fixed 45 to arched members constituting the striker system, the spindles on each system being relatively spaced apart in such a manner that the spools of one system precede the spools of the other system to provide a reciprocal 50 clearance between the two circular tracks, a binding thread subsequently guided upwardly supported on the stationary spindle of the plate system and a plate provided with loops for the guiding of the thread carried 55 upon said spindle and extending under the striker system up to the position of intersection of the joint circular tracks, substantially as described. 60
- 15 5. A device for the manufacture of tape, webbing, gimp, braid and similar materials comprising in combination a plate spool system and a striker spool system distanced apart and the one vertically displaced in relation to the other both adapted for revolution in the same or in opposite directions, the track of the striker system being suitably cut-away to enable the unhindered crossing of the plate spools, means for driving the 20 systems from a joint shaft enabling an interior or an exterior drive to be employed for the strikers, spool spindles carried by the plate system and spool spindles fixed to arch members constituting the striker system said 25 arched members being longer than the cut-away portion in the gang track of the striker system, the spindles on each system being relatively spaced apart in such a manner that the spools of one system precede the spools 30 of the other system to provide a reciprocal 35

In testimony whereof, we have signed our 65 names to this specification at Cologne, Germany this 12th day of February, 1926.

CARL ERNESTUS.
WILHELM LUSEBRINK.
